CLAIM

The ornamental design for a chair as shown and described.

DESCRIPTION

FIG. 1 is a top, front, left side perspective view of a chair showing my new design;

FIG. 2 is a front perspective view thereof;

FIG. 3 is a rear perspective view thereof;

FIG. 4 is a left side perspective view thereof;

FIG. 5 is a right side perspective view thereof; and,

FIG. 6 is a top plan view thereof.

The broken lines represent stitching on the seat portion of the chair. All other broken lines represent portions of the chair that form no part of the claimed design.
